UNITED STATES PATENT OFFICE.

CHARLES A. WEEKS, OF PHILADELPHIA, PENNSYLVANIA, ASSIGNOR TO THOMAS R. PATTON AND FREDERICK C. MENCKE, BOTH OF PHILADELPHIA, PENNSYLVANIA.

PROCESS OF MAKING COKE AND RECOVERING BY-PRODUCTS.

1,127,949.

Specification of Letters Patent.

Patented Feb. 9, 1915.

Application filed July 25, 1911. Serial No. 640,472.

To all whom it may concern:

Be it known that I, CHARLES A. WEEKS, a citizen of the United States, and a resident of Philadelphia, county of Philadelphia, State of Pennsylvania, have invented an Improvement in Processes of Making Coke and Recovering By-Products, of which the following is a specification.

My invention has reference to processes for making coke and recovering by-products and consists of certain improvements which are fully set forth in the following specification and accompanying drawings, which form a part thereof.

15 The nature of my invention will be better understood by first referring to the general method of making coke now in general use and pointing out the objections thereto and then indicating wherein my invention overcomes said objections.

When bee-hive or rectangular ovens are used in making coke from bituminous coal and the ovens fired alternately, the upper part of the coal charge becomes first heated 25 by reason of the presence of sufficient air to produce combustion in the upper portion of the oven when sealed for carbonizing. By reason of this firing of the coal from the top and requiring it to burn downwardly, the upper part of the charge is brought first to a point of incandescence, and when gas or other matter containing sulfur ammonia, tar, etc. are distilled from the lower part of the charge they pass upward through this 35 highly heated body of incandescent coal and are decomposed or burned up. The tar and sulfur contents of the coal charge are formed between 200° C. and 500° C., and the ammonia between 500° C. and 700° C., and

40 when the temperature of the oven reaches the carbonizing stage for the production of coke, namely, about 1400° C. these products are decomposed, the tar burned, the sulfur content converted in the presence of carbon

45 into carbon bisulfid and hydrogen sulfid, and the ammonia converted into hydrocyanic acid. The sulfur content of the coal being converted into carbon bisulfid and hydrogen sulfid, in passing upward from the lower

50 part of the charge in the oven, through the incandescent highly heated body of coal located in the upper part of the said charge, during the process of carbonizing the coke, said compounds will, instead of passing away with other gases generated, remain in

compound forms with the coke as an impurity to the extent of not less than 60% of the sulfur contained in the coal. This, the usual process of making coke in the bee-hive and rectangular ovens, is a slow and wasteful one, the carbonizing is uncertain as to output, the time of burning required is excessive and the contained impurities are highly objectionable, and the process is wasteful as to values that may be recovered. The only advantages are the low construction cost, and the production of a strong metallurgical coke.

55 My invention broadly consists in treating the coal to be carbonized in ovens and the combustion carried on from the bottom upward during the process of distillation, whereby the distillates are caused to be positively drawn off through a comparatively cool upper zone and hence without changing 70 their chemical composition, after which the carbonization is completed in the usual manner; the by-products thus eliminated from the coking coal being subjected to treatment for their recovery. More specifically the 75 process and means employed may be described as follows:

In my improved process of recovering by-products, and the purification of gas produced during the carbonizing of the coal, I 85 make a better grade of strong metallurgical coke, secure all the advantage of low construction cost, and good coke, and all the good parts of the by-product—savings of the costly retort ovens, in which the coal is 90 charged into retorts to which heat is applied from the outside, recuperatively or otherwise.

In carrying out my invention, I take the rectangular ovens for new construction as 95 affording the better type for my invention, and provide a gas vent pipe to the upper part of each oven, with a closing valve therein so that the ovens can be cut out of operation at will, said gas vent being in turn connected with a large gas main which leads to a gas cooler and settling tank where the dust and tar settle out of the gas and the gas then drawn by suction into and through a rotary suction washer where it is thoroughly 100 washed and delivered, to be stored in a reservoir or tank.

In conjunction with the above described means I provide the bottoms of the ovens with inlets through which air, steam, or 110

both, may be admitted into the ovens at will; and the said air may be injected by pressure or by induction from the suction induced by the action of the gas-condensing 5 tower and rotary washer referred to above. I also employ as part of my improved system, an apparatus such as shown whereby an amount of water may be injected on top of the coal charge, and against the roof of 10 ovens in order to reduce the temperature and to retard the consumption of the charge due to spreading and activity of the ignition; it being my purpose to fire the coal charge from the bottom of oven and retard 15 the firing of the upper part of charge to it at a low temperature until the gases, distilled from the lower part of the charge, are brought to a higher temperature first, and then permitted to pass upward through 20 the relatively cooler zone, by means of the induced draft applied to gas vent in top of ovens, and from the oven under suction produced in the cooler and rotary washer. By reason of the fact, that the distilled 25 gases and other products are taken off under constant suction at temperatures at which they are formed, instead of passing through a highly heated zone of carbonizing coal, they are not decomposed and the sulfur 30 will be largely eliminated from the coke, and will go forward with the other gases, the tar will not be consumed and the ammonia will not be decomposed and converted 35 into hydrocyanic acid, but will, if desired, be absorbed by the water in which the gas is washed during the process of purification.

In order to produce a strong metallurgical coke by my improved process, after 40 the by-products are distilled from the coal, the air for combustion used in igniting the lower part of the charged coal is shut off by means of valves, the valve in the gas vent leading to the gas main is closed, and 45 the vent or vents used in charging coal to ovens are to be opened and the carbonizing of the coke continued to completion.

This new method of coking coal insures 50 perfect control of the coking conditions as to firing, and shortens time of burning required, as well as insuring the production of a superior coke.

Referring to the drawings: Figure 1 is 55 a front elevation of a coking and recovery apparatus suitable for the carrying out of my improved process; and Fig. 2 is a cross section of the same.

2 are a plurality of rectangular coking ovens having charging vents 3 and dis- 60 charging ends 6 having removable doors 7. Vent outlets are extended from the top of the ovens by pipes 12 having valves 14. Each of these pipes 12 connect with a large gas main 13 which leads into the scrubber 65 or cooling tower 16. The cooling tower is

provided with pipes 17 for spraying sulfate liquor upon the gases delivered into the tower. From the cooling tower 16 the gases pass by pipe 19 into the suction rotary washer 20 where the ammonia, not 70 already absorbed in the tower 16, is absorbed by the sulfate liquor in said washer. The purified gas leaves the washer 20 by pipe 21 and may pass to a suitable holder for use in operating gas engines, fuel in 75 metallurgical operations or for illuminating purposes after being carbureted in the usual way. The sulfate liquor of the washer 20 may be drawn off by pipe 23 and, by pump 18, forced into spray through the spray 80 pipes 17 of the tower 16. The sprayed liquor collects in the bottom of tower and flows by pipe 22 into the washer 20, and in this way the sulfate liquor is circulated and becomes of uniform character. 85

The suction washer 20 may be of any suitable construction so long as it produces a suction or vacuum on the tower and upon the gases generated in the ovens, for the purpose of sucking them away from the 90 ovens as rapidly as produced.

11 is an air main extending from a blower 15, and along the series of ovens. Opening from this main and extending below the floor of each oven, is an air pipe 8 having 95 nozzles or twyvers 9 for supplying the air to the bottom of the body of coal in the oven.

24 is a spray pipe which is supported on a truck 26 running upon a track 27 along the series of ovens; and said pipe 24 may 100 be adjusted into the upper part of each of the ovens by the adjusting devices 25 on the truck whenever it is desired to chill the coke in the oven before discharging the same. Any suitable means for spraying the coke 105 with water may be employed in the place of that shown.

The coal is fed into the ovens through the vents 3 from the hoppers 5 carried on the lorry 4 which runs upon a trackway along 110 the top of the ovens. When the gases are to be drawn off to the tower 16 the vents 3 are sealed by suitable covers.

Briefly stated, the operation of this apparatus is as follows:—The coal is charged 115 into the oven through the vents 3, the doors 7 being put in place, combustion started at the bottom assisted by the blast from the twyvers 9. The vents 3 are closed and valve 14 opened. The gases distilled from the 120 coal are drawn off by the suction in the main 13 through pipe 12. The gases thus pass off without being superheated by having to pass through incandescent coal at the top of the charge as heretofore occurred. 125 After the distillation of the gaseous or volatile constituents of the coal has taken place the valve 14 is closed and the vents 3 are opened to finish the carbonization of the charge to bring it to the desired condition 130.

of coke. During this latter operation the air valve 10 is closed so that the blast from the twyers 9 is shut off and only the small leakage of air through the doors 7 need be relied upon for this part of the coking operation. When the carbonization is completed, the upper portion of one of the doors 7 is removed, the spray pipe 24 run into the oven and the charge chilled by water spray, and the charge ultimately discharged.

The special features of the process have heretofore been fully described and hence it will not be necessary to again refer to them. The method of coking coal herein described insures perfect control of the coking conditions as to firing, and shortens the time of burning required, as well as insuring the production of a superior coke.

The gases which pass off from the ovens will contain ammonia which may be recovered by the means shown or in any other suitable manner, though this does not form any part of the present invention.

Having now described my invention, what I claim as new and desire to secure by Letters Patent, is:—

1. The herein described process of coking coal, which consists in charging a closed oven with coal, burning the coal from the bottom upward to distil off the volatile constituents, delivering the volatile constituents into a common space within the oven above the coal, drawing off said volatile constituents by suction applied to the common space whereby the suction does not concentrate a draft upon particular portions

of the coal said suction continuing until the coal becomes fully heated from the bottom to the top, and finally shutting off the suction and completing the coking of the coal.

2. The herein described process of coking coal which consists in charging the coal into a closed oven, burning the coal from the bottom upward to distil off the volatile constituents, positively drawing off said volatile constituents and controlling the temperature by regulating the supply of air to the bottom of the coal charge while the coal becomes heated from the bottom to the top, then opening the oven at the top and arresting the drawing off of the volatile constituents, and continuing the carbonization of the coal until it is converted into the desired quality of coke.

3. The herein described process of coking coal which consists in charging the coal into a closed oven, burning the coal from the bottom upward by a blast of air delivered to the bottom of the heated charge to distil off the volatile constituents, drawing off said volatile constituents as the coal becomes fully heated from the bottom to the top and finally shutting off the blast to the oven and opening the upper portion of the same to the atmosphere for completing the carbonization of the coal into coke.

In testimony of which invention, I hereunto set my hand.

CHARLES A. WEEKS.
